UNITED STATES PATENT OFFICE.

RUDOLF LORENTZ, OF STETTIN, GERMANY.

AMERICAN JOURNAL FOR BOOKKEEPING PURPOSES.

Application filed May 19, 1923. Serial No. 640,108.

To all whom it may concern:

Be it known that I, RUDOLF LORENTZ, a citizen of the free State of Prussia, German Republic, residing at 35, Friedrich Karlstrasse, Stettin, Germany, have invented certain new and useful Improvements in American Journals for Bookkeeping Purposes, of which the following is a specification.

10 The well known American journals used for bookkeeping purposes contain leaves, which are in a certain manner imprinted with columns. These leaves can only be utilized for a small number of accounts and 15 their size is inconvenient for handling. A comparatively great amount of paper is required, as they are only partly utilized for booking-notes. A further drawback consists therein, that these large sheets of paper 20 have to be turned over, for carrying over accounts and a survey of the result can, in the usual application for a sundry account, only be obtained at the end of a month.

To avoid these drawbacks, the leaves of 25 the journal, held together in bookform, are according to this invention printed with a carry-over or special column on the page, which is located to the right when the book is opened, and arranged parallel to and on 30 the outer high edge of the leaf. It is a distinct feature of the invention, that this special column is provided with cross lines differing from the rest of the leaf, and this arrangement is of the greatest importance for 35 handling the book, since a large number of accounts can thus be kept and the remaining part of the leaf can be completely utilized.

The left hand leaf from the middle of the open book, is for carrying-over purposes 40 folded in such a manner, that the carry-over column printed on the back of the same becomes visible and the leaf is so far moved towards the right, that the column visible in consequence of folding over, is, with its 45 entirely outward edge located in front of the summing-up column of the right hand leaf upon which accounts are to be carried.

After this preparatory work, carrying can be effected without turning over leaves. 50 Since holding of the backward folded leaf is cumbersome and inconvenient, an auxiliary arrangement is practicably employed, which retains the folded sheet in proper position for carrying-over purposes.

As example for executing the invention, 55 a journal, provided with the said auxiliary arrangement, is illustrated by the drawing.

Fig. 1 illustrates the journal with the auxiliary device attached, the folded sheet being retained by the auxiliary arrangement. 60

Fig. 2 shows the auxiliary arrangement in side-view.

Fig. 3 is a vertical section on line A—B of Fig. 2 taken in the direction of the arrow.

Fig. 4 is a plan-view of the auxiliary arrangement after removing the cover-slat of the same. 65

The auxiliary arrangement consists of two wooden slats *a* and *b*, between which an equally long, narrow slat *c* is provided. 70 The two slats *a* and *b* are firmly connected by screws *d*, whereby the slat *c*, which may be secured in any other suitable way, is firmly clamped. The slat *a* is provided with two projecting arms *e* and *f*, fastened 75 by screws *g* and a pivoted arm *i*, revolving around a screw-bolt *h*, the arm *i* being arranged between the rigid arms *e* and *f*.

For limiting the rotation of the arm *i*, a rigid stop *k* is provided secured on one of 80 the slats. On each of the slats *a* and *b*, a plate *l* and *m* is secured on the edge thereof by means of pins. The two plates are provided with cuts by which a slot *o* is formed, having oblique tightening edges *p*. Two 85 angle-pieces *q* and *r* are fastened on the edge of the slat *a* thereby forming lugs *s* and *t* bent at right angles.

This auxiliary device is placed upon the 90 right hand leaf of the open journal to be provided with notes in such a way that the edge *u* of the same and the edge *v* of the auxiliary device cover each other. The preceding leaf *w* of the book is then folded, for 95 the purpose of reading the amounts to be carried, by placing the edge *x* below the lugs *s* and *t* and against the angle-pieces *q* and *r*.

The arm *i* is now turned into the position 100 shown in Fig. 4 in dotted lines. The arm thus touches first the tightening edges *p* and under further pressure in the same direction forces the wooden elastic slats *a* and *b* apart. This slight spreading is sufficient for clamping the leaf of the book firmly between the slat *b* and the lugs *s* and *t*, so that the same can not slip from the auxiliary device. The latter is then placed with the clamped leaf 105

in the position indicated in Fig. 1, whereupon carrying of the accounts can be effected as required.

After this has been done, the lever is returned to the position indicated by full lines in Fig. 4, whereby the slat *b* is removed from the lugs *s* and *t*, and the previously clamped leaf is thus released. The auxiliary device can now be removed and the book closed.

The journal is used as follows: The results of accounts calculated according to the summary column are entered in the special column by the side of the respective numbers of accounts, one below the other and the balance of the page, as well as the correspondence with the summary column thereby proved by addition. This applies to the first page.

In summing up the second page, the first page is folded by means of the described device and the results of the first page are in view with the booked amounts of the second page.

The results of accounts of the first page are now, in ascertaining the results of the second page, added etc., the work being effected as explained for the first page. Placing the now ascertained results besides the respective numbers of accounts on the right hand edge of the carry-over column of the second page, they are added for the purpose of proving the page-balance with the result of the summary column and this process is continued page by page to the end of the month or year.

The advantages of the invention consist mainly therein, that an unlimited control can be effected within the scope of the work, whereby the results are arranged below each other instead of otherwise besides each other. In case of suitable arrangement of lines, 80 accounts can be handled in one carry-over column and about 160 in two carry-over columns.

Carrying is effected very conveniently and the sundry account is separated in every page-addition. Bookkeeping of each page is thus finished. The sundry account can be completely utilized, as the separation of the page-accounts can easily be effected, especially under employment of numbers of accounts instead of names. Control and examination are extraordinarily facilitated. All small leaves are eliminated. A journal of only 23 cm. width, called narrow shape, enables the obtaining of the same effect as a journal of one meter width under almost equal use of lines.

I claim:

1. In combination with the pages of a book, a holding device for folding and keeping a page folded in order to expose a part of the page beneath it for carrying over purposes, said device comprising means for

gripping the page of the book in the folded position; and means for locking the page to the gripping means.

2. In combination with the pages of a book, a holding device for folding and keeping a page folded in order to expose a part of the page beneath it for carrying over purposes, said device comprising a pair of spaced slats; angle pieces secured to one of said slats; and means for forcing the other of said slats against said angle pieces for holding the page of the book in the folded position.

3. In combination with the pages of a book, a holding device for folding and keeping a page folded in order to expose a part of the page beneath it for carrying over purposes, said device comprising a pair of slats; means secured to one of said slats for holding the page of the book in the folded position; and means for operating said slats to secure or release said page.

4. In combination with the pages of a book, a holding device for folding and keeping a page folded in order to expose a part of the page beneath it for carrying over purposes, said device comprising a pair of slats; securing means on one of said slats; and means for forcing the other of said slats toward said securing means so that the last-named slat and said securing means will securely hold said page of the book in the folded position.

5. In combination with the pages of a book, a holding device for folding and keeping a page folded in order to expose a part of the page beneath it for carrying over purposes, said device comprising a pair of spaced slats; angle pieces secured to one of said slats; an arm pivoted to one of said slats; and means for forcing said slats apart upon actuation of said arm whereby said page will be retained in the folded position between said angle pieces and the other of said slats.

6. In combination with the pages of a book, a holding device for folding and keeping a page folded in order to expose a part of the page beneath it for carrying over purposes, said device comprising a pair of spaced slats; angle pieces secured to one of said slats and each provided with a lug; an arm pivoted to one of said slats; a stop for said arm; and means for forcing said slats apart upon actuation of said arm to said stop to thus force one of said slats against said lugs to hold the page of the book therebetween in the folded position.

7. In combination with the pages of a book, a holding device for folding and keeping a page folded in order to expose a part of the page beneath it for carrying over purposes, said device comprising a pair of slats; an arm pivoted to one of and between said slats; means secured to one of said

slats for holding the page of the book in the folded position; and means for forcing said slats apart upon actuation of said arm to cooperate with, and the page will be secured by, said first-named means.

8. In combination with the pages of a book, a holding device for folding and keeping a page folded in order to expose a part of the page beneath it for carrying over purposes, said device comprising a pair of slats; an arm pivoted to one of and between said slats; means secured to one of said slats for holding the page of the book in the folded position; a stop for said arm for

limiting the movement thereof; and means for forcing said slats apart upon actuation of said arm to cooperate with, and the page will be secured by, said first-named means.

9. In combination with the pages of a book, a holding device for folding and keeping a page folded in order to expose a part of the page beneath it for carrying over purposes, said device comprising a pair of slats; and means on said slats for gripping and retaining the page of the book in the folded position.

In testimony whereof I affix my signature.

RUDOLF LORENTZ.
